UNITED STATES PATENT OFFICE.

CHARLES E. WALLER, OF ALLENTEWON, PENNSYLVANIA, ASSIGNOR TO INDEPENDENT
NON-FREEZING POWDER COMPANY, OF NEWARK, NEW JERSEY, A CORPORATION OF
NEW JERSEY.

NITROSTARCH EXPLOSIVE.

1,305,845.

Specification of Letters Patent. Patented June 3, 1919.

No Drawing.

Application filed January 22, 1915. Serial No. 3,783.

To all whom it may concern:

Be it known that I, CHARLES E. WALLER, a citizen of the United States, and a resident of Allentown, Lehigh county, Pennsylvania, have invented certain Improvements in Nitrostarch Explosives, of which the following is a specification.

My invention relates to nitro-starch explosives.

10 Heretofore nitro-starch explosives have ordinarily been produced and used in the form of a fine powder with small proportions of suitable oils added thereto to give consistency and to render waterproof. These 15 explosives have been of the class known as high explosives containing comparatively high percentages of nitro-starch and having as their characteristic feature when exploded a relatively quick action. For some blasting 20 operations it is desirable to use explosives of slow action—that is, having more of a heaving force than a shattering effect. The explosives which have heretofore been used for this class of work are black powder 25 and the so-called low powders containing small percentages of nitro-glycerin. It is the object of this invention to provide a similar slow acting nitro-starch explosive.

The difficulty which has heretofore been 30 experienced by experimenters in search of such a nitro-starch explosive has been that these explosives in the ordinary form have proven too insensitive to detonation when the percentage of nitro-starch has been reduced to the point where the action of the explosive is as slow as is necessary to meet the requirements of the class. For instance, mixtures, containing from ten per cent. (10%) to fifteen per cent. (15%) of nitro-starch together with suitable percentages of an oxygen bearer, such as nitrate of soda and of combustible matter such as sulfur and charcoal, fail to explode with an ordinary detonating cap even when confined under 45 such conditions as exist in practice. In fact, with nitro-starch as high as twenty-five per cent. (25%), mixed with certain desired proportion of oxygen carrier and combustible, the powder in the ordinary form of nitro-starch powders cannot be detonated under 50 all conditions met in ordinary practice. I have discovered that by granulating such mixtures, however, in accordance with the method which I shall describe, the resultant 55 granular explosives will explode under the

conditions which exist in blasting operations with as low a proportion of nitro-starch as five per cent. (5%), and various mixtures containing from five per cent. (5%) to twenty-five per cent. (25%) nitro-starch, which before could not be used in practice, become, in the form in which I produce them, entirely practical. Furthermore, the rate of detonation of such explosives is slow and suitable for such blasting operations as mentioned above.

I describe my method of producing the granular nitro-starch explosives as follows:

As an oxygen carrier I employ nitrate of soda, or any equivalent oxygen carrier commonly employed for such purpose. For combustible matter I use charcoal or any similar combustible carbonaceous material and sulfur. Nitro-starch is used as the explosive base. Any suitable antacid may be employed, and if desirable a small percentage of a suitable waterproofing oil may be added. As a binder I use starch paste.

In preparing the explosive I first thoroughly mix, by any suitable means, the various ingredients other than the nitro-starch. I then add and thoroughly mix in the nitro-starch. To the mass thus obtained I add liquid starch paste prepared by heating one part of corn starch with twenty-five parts of water. The explosive mixture and the starch paste are then thoroughly mixed and incorporated. The entire mass is then rubbed through a screen, preferably of four to six mesh, on to trays, and dried. The dried mass is then readily broken up into the desired granular form. This method is to be sharply distinguished from that in which a mass is compressed and grained, as in the manufacture of gun-powder. Compression would prevent detonation and my product must be uncomressed.

In carrying out my process, I have found that good results can be obtained by adding twenty-six (26) parts, by weight, of the starch paste, to ninety-nine (99) parts, by weight of the mixed explosive, the explosive in such case, when finally prepared containing about one per cent. (1%) of dried starch. It is to be understood, however, that I do not confine myself to these precise proportions, as the relative amounts of the paste and explosive mixture may be varied without departing from the substance of my invention. I prefer that the final prod-

uct should not contain more than four per cent. (4%) of dried starch.

5 Corn starch is the binder with which I have had success, but other starchy or similar materials capable of forming a similar paste might be employed with more or less success. I prefer to employ corn-starch.

10 Granulated uncompressed nitro-starch explosives, prepared as above, have decided advantages over other granular explosives. They are stronger than black powder and are much more waterproof. They do not freeze as do low powders containing small percentages of nitro-glycerin. The character of their action on explosion is slow and much more suitable to the work for which they are intended than are any of the granular chlorate explosives. The matter of first 15 importance is that they can be detonated under practical service conditions with ordinary detonating caps, while the same mixture in the ordinary form could not be so used.

20 An example of one formula which I have used with good results is as follows:

Nitro-starch	10	%
Sodium nitrate	73	
Sulfur	7.5	
Charcoal	7.5	
Calcium carbonate	1	
Dried starch paste	1	
	100	%

35 I do not confine myself to the above proportions, however, as these may be varied within certain limits and still give satisfactory results in varying degrees. The percentages which I believe may be used to obtain the 40 results which I have described are as follows:

Nitro-starch	From	5% to 25%
Sodium nitrate	"	50% to 85%
Sulfur	"	2% to 10%
Charcoal	"	2% to 10%
Calcium carbonate	"	1% to 3%
Dried starch paste	"	1% to 3%

50 Nor do I confine myself to the specific oxygen bearer, combustible material or antacid named above. For instance, instead of sodium nitrate, potassium nitrate or barium nitrate or any other well known oxygen carriers may be used. In the place of char-

coal there may be used lamp black, finely ground coal or any suitable combustible carbonaceous material. The calcium carbonate may be replaced with sodium bi-carbonate or any other well known antacid.

60 I claim:

1. A granular nitro-starch explosive whose sole detonating ingredient is nitro-starch; the percentage of nitro-starch present being such that the explosive is incapable of detonation in non-granular bulk form under 65 ordinary conditions.

2. A granular nitro-starch explosive containing nitro-starch as the sole detonating ingredient; said nitro-starch being present to the extent of approximately five to 70 twenty-five per cent. by weight of the whole explosive.

3. A granular, uncompressed, detonating explosive containing nitro-starch, and including a binder of agglutinizing material; 75 said nitro-starch being present to the extent of approximately five to twenty-five per cent. by weight of the whole explosive.

4. A granular, uncompressed, detonating explosive containing five to twenty-five per 80 cent. by weight of nitro-starch, and including a binder of starch paste which, when dry, approximates one to three per cent. by weight of the entire mixture.

5. A granular, uncompressed, detonating 85 explosive containing five to twenty-five per cent. by weight of nitro-starch, an oxygen carrier, combustible carbonaceous material, and a starchy binder approximating one to three per cent. by weight of the entire mixture. 90

6. A granular, uncompressed, detonating explosive containing five to twenty-five per cent. by weight of nitro-starch, fifty to 95 eighty-five per cent. of sodium nitrate, two to ten per cent. of sulfur, two to ten per cent. of charcoal, one to three per cent. of calcium carbonate, and a binder of starch approximately one to three per cent. by weight of the entire mixture. 100

In testimony whereof, I have signed my name to this specification, in the presence of two subscribing witnesses.

CHARLES E. WALLER.
